UNITED STATES PATENT OFFICE

142,105

DESIGN FOR A TERMINAL SOCKET

Paul Meminger, Los Angeles, Calif.

Application April 23, 1945, Serial No. 119,155

Term of patent 14 years

(CL. D26—1)

To all whom it may concern:

Be it known that I, Paul Meminger, a subject of the King of England and residing at Los Angeles, in the county of Los Angeles, State of California, have invented a new, original, and ornamental Design for Terminal Socket, of which the following is a specification, reference being had to the accompanying drawing, forming part thereof, in which:

Fig. 1 is a perspective view of the terminal socket as seen from one end thereof showing my new design;

Fig. 2 is a perspective view of the terminal socket as seen from the end thereof opposite that shown in Fig. 1;

Fig. 3 is a plan view of the terminal socket;

Fig. 4 is a view of the terminal socket as seen in side elevation;

Fig. 5 is a view in end elevation.

I claim:

The ornamental design for a terminal socket, substantially as shown.

PAUL MEMINGER.
